(57) **CLAIM**

The ornamental design for a plastic food container, as shown and described.

DESCRIPTION

FIG. 1 is a front perspective view of a plastic food container embodying the new design;

FIG. 2 is a front elevation view thereof with the base having the lid secured thereon;

FIG. 3 is a rear elevation view thereof with the base having the lid secured thereon;

FIG. 4 is a left side elevation view thereof with the base having the lid secured thereon;

FIG. 5 is a right side elevation view thereof with the base having the lid secured thereon;

FIG. 6 is a top plan view thereof with the base having the lid secured thereon;

FIG. 7 is a bottom plan view thereof with the base having the lid secured thereon;

FIG. 8 is a front exploded perspective view thereof with the lid removed from the base to provide a partial view of the interior of the container;

FIG. 9 is a front elevation view of the lid of the container, shown separately for completeness of illustration;

FIG. 10 is a rear elevation view of the lid of the container, shown separately for completeness of illustration;

FIG. 11 is a left side elevation view of the lid of the container, shown separately for completeness of illustration;

FIG. 12 is a right side elevation view of the lid of the container, shown separately for completeness of illustration;

FIG. 13 is a top plan view of the lid of the container, shown separately for completeness of illustration;

FIG. 14 is a bottom plan view of the lid of the container, shown separately for completeness of illustration;

FIG. 15 is a front elevation view of the base of the container, shown separately for completeness of illustration;

FIG. 16 is a rear elevation view of the base of the container, shown separately for completeness of illustration;

FIG. 17 is a left side elevation view of the base of the container, shown separately for completeness of illustration;

(Continued)

FIG. 18 is a right side elevation view of the base of the container, shown separately for completeness of illustration; FIG. 19 is a top plan view of the base of the container, shown separately for completeness of illustration; and, FIG. 20 is a bottom plan view of the base of the container, shown separately for completeness of illustration.
